UNITED STATES PATENT OFFICE.

JULIUS BING, OF DETROIT, MICHIGAN, ASSIGNOR OF ONE-HALF TO CHARLES J. HOLTON, OF DETROIT, MICHIGAN.

TRICK CIGAR.

No. 887,759.

Specification of Letters Patent.

Patented May 19, 1908.

Application filed September 1, 1906. Serial No. 332,901.

To all whom it may concern:

Be it known that I, JULIUS BING, a citizen of the United States of America, residing at Detroit, in the county of Wayne and State of Michigan, have invented certain new and useful Improvements in Trick Cigars, of which the following is a specification, reference being had therein to the accompanying drawings.

This invention relates to new and useful improvements in trick cigars and has for its object to make a cigar which will spread out and have the appearance of an old paint brush shortly after being lighted without danger of the parts flying in the smoker's face.

To this end the invention consists in the peculiar construction, arrangement and combination of parts all as more fully herein-after described and shown in the accompanying drawings, in which

Figure 1, is a vertical central section through a cigar embodying the invention; Fig. 2, a plan view of the spring in condition as it is placed in a cigar; and Fig. 3, a plan view showing the spring spread out.

In the drawings 1 is the filler and 2 the wrapper of a cigar as in ordinary use.

The invention consists in embedding therein a spring 3 composed of a piece of spring wire bent into V-form with a single coil 4 at its base and the arms 5 of which are united at their free ends by a string or loop 6 of inflammable material adapted to hold the arms under tension and to release the same when the cigar has been smoked but a short while.

By making the spring arms relatively long and placing the looped end near the outer

end of the cigar there will be no danger of the parts flying into the eyes of the smoker as the spring arms as soon as released will spread 40 the cigar apart giving it much the appearance of a paint brush.

What I claim as my invention is:

1. In a trick cigar the combination with a cigar body of a spring embedded therein and 45 connecting means holding the spring under tension whereby it is adapted to be released by the burning of the cigar.

2. In a trick cigar the combination with a cigar body of a spring embedded therein 50 formed with arms adapted to lie in the longitudinal plane of the cigar and a fusible loop uniting the outer ends thereof.

3. In a trick cigar the combination with a cigar body of a spring embedded therein 55 formed with arms united by a coil at the inner end and combustible means uniting the free ends of said arms and adapted to be released by the smoking of the cigar.

4. In a trick cigar the combination with a 60 cigar body of a spring embedded therein and formed with a coil at one end and arms adapted to lie in the longitudinal plane of the cigar with their free ends near the outer end thereof and a loop of combustible material 65 uniting the free ends of said arm under tension adapted to be released by the smoking of the cigar.

In testimony whereof I affix my signature in presence of two witnesses.

JULIUS BING.

Witnesses:

OTTO F. BARTHEL,
CHARLES B. SHUMWAY.
